UNITED STATES PATENT OFFICE.

JAMES SEBBORN ATKINSON, OF LOUISVILLE, KENTUCKY, ASSIGNOR OF ONE-FOURTH TO WILLIAM C. ATKINSON, OF NASHVILLE, TENNESSEE.

VALVE FOR PUMPING-ENGINES.

SPECIFICATION forming part of Letters Patent No. 664,114, dated December 18, 1900.

Application filed May 26, 1900. Serial No. 18,075. (No model.)

To all whom it may concern:

Be it known that I, JAMES SEBBORN ATKINSON, residing at Louisville, in the county of Jefferson and State of Kentucky, have invented a new and useful Improvement in Valves for Pumping-Engines, of which the following is a specification.

My invention is an improvement in automatic valve attachments for pumping-engines.

The details of construction, arrangement, combination, and operation of parts are hereinafter described with reference to the accompanying drawings, in which—

15 Figure 1 is a central longitudinal section of the steam or motor portion of my pump. Fig. 2 is a vertical section of the same on line 2 2, Fig. 1. Fig. 3 is a perspective view of the steam-chest and its base-plate. Fig. 4 is a 20 perspective view of the piston-cylinder. Fig. 5 is a perspective view of the automatic valve.

The piston A of the engine, which is adapted to reciprocate in the cylinder B, is of the trunk type and has a slightly-greater length 25 than the stroke of the pump, with which it is in practice connected by the rod C in the usual way.

The steam-chest D and its contained valve E are cylindrical in form, and the chest is arranged parallel with the side of the piston-cylinder A, to which it is bolted. The valve-chest D has a flat bed or bed-plate F, (see Fig. 3,) which is adapted to fit upon the flat top G of the piston-cylinder B. (See Figs. 2 30 and 4.) The valve E has a central chamber 1, to which live steam has constant access through a side and top port 2 and the coincident but narrower one 3 in the chest D. Said chamber has two ports 4 4^a on the under side, 35 which as the valve E shifts alternately register with the long and curved induction and exhaust ports 5 5^a, leading in opposite directions to the ends of piston-cylinder B.

The valve E is provided with circumferential chambers or grooves 6 6^a between each of its ends and the central chamber 1, such grooves forming steam spaces or passages that serve alternately for exhaust-ports as the valve reciprocates. In other words, said 40 grooves or passages 6 6^a alternately establish communication between the passages 5 and

5^a, respectively, and the main exhaust cavities or grooves 9, (see Figs. 2 and 4,) which are formed in the valve-seat and lead to the exhaust-nozzle 7. Thus at each endwise movement of the valve E one of the grooves or spaces 6 6^a coincides with one of the main ports 5 5^a, so that exhaust takes place from the nozzle in the side of the steam-chest.

55 The small passages 8 8^a, which appear as mere grooves or depressions in the face of the part G, conduct steam from the piston-cylinder B to the ends of the steam-chest and connect with the former at points which are a little to one side of the center, as shown in Fig. 1. 60 They are curved, (see Fig. 4,) so as to pass around the combined inlet and exhaust passages 5 5^a.

65 A semicircular groove 9 (see Fig. 3) is formed in the under side of the bed-plate F of the steam-chest D, and this communicates at its center with the port 9^a, (see Figs. 2 and 4,) that leads to exhaust-nozzle 7. The side portions of groove 9 communicate alternately with ports 5 5^a to allow exhaust at one or the 70 other end of the cylinder B at each half-reciprocation of the piston A.

75 The formation of the passages 8, 8^a, and 9 as grooves or depressions in the face G effects a considerable economy in the construction of 80 the engine as compared with cored castings, which often prove defective and are therefore worthless.

85 From the foregoing description the operation of the valve E may now be understood. As shown in Fig. 1, the piston A has completed its movement to the right and the left-hand end of the cylinder B has exhausted through the communicating passage 5, while steam has also passed through the left-hand 90 passage or port 8 and acted on the left-hand end of the valve E, and thus shifted it also to the right, and live steam is being admitted to the right-hand end of cylinder B from the central valve-chamber 1 through the right-hand 95 passage 5^a, so that the next movement of the piston A will be from right to left, whereupon the right-hand passage 8^a to steam-chest D will be uncovered and steam thereby admitted to act on the nearest or right-hand end of the 100 valve E and shift it to the left. By this operation the port 4^a in valve E will no longer

communicate with the right-hand passage 5^a, leading to the right-hand end of cylinder B, but communication will be established between said passage and the exhaust. Thus 5 the piston-valve E acts automatically to allow alternate induction and exhaust of steam to and from the piston-cylinder through the same passages and is itself acted on by live steam, and thereby shifted at each half-reciprocation of the piston A, so as to cut off steam at the right moment.

The steam which acts on and actuates the valve A may be allowed to exhaust through the main passages 5 5^a, by which it entered 15 the cylinder B; but to make sure provision for thorough exhaust ports 10, Figs. 1 and 2, are formed in the valve-seat, the same extending horizontally to connect with the main exhaust cavities or grooves 9. The said ports 20 are located such distance from the ends of the valve-chamber that the valve E uncovers and opens them alternately as it reaches the limit of its stroke.

To prevent the valve E turning or rotating 25 about its axis, I provide a rectilinear guide for the same by means of a screw 11, Fig. 2, which passes through the side of the steam-chest D, its smooth or threadless end projecting into a longitudinal slot 12, Fig. 1, in the 30 side and central portion of the valve.

In case the engine is used vertically I provide means for counterbalancing the weight 35 of the valve, so that it may not drop prematurely by gravity, and for this purpose the valve E may have a rod or small stem projected through the upper end of the steam-chest and working in a stuffing-box having the usual form of gland, by which friction on the said stem may be regulated as required 40 to overcome the effect of gravity.

Having thus described my invention, what I claim, and desire to secure by Letters Patent, is—

1. The combination with a cylinder-piston, 45 and steam-chest and intermediate exhaust-passages of a valve adapted to reciprocate in the steam-chest, and having a central cham-

ber provided with an induction-port on one side and two eduction-ports on the other, and also with grooves or exhaust-ports located laterally from said chamber, passages each communicating alternately with said eduction-ports and exhaust-ports and leading to the ends of the piston-cylinder, whereby they serve alternately for induction into and exhaust from the cylinder, and two small steam-passages connecting the ends of the steam-chest with the cylinder on each side of the center, whereby the valve is automatically reciprocated to admit and exhaust steam, 60 substantially as shown and described.

2. The combination, with cylinder, piston, steam-chest and valve having a central ported chamber and lateral exhaust-spaces, of combined induction and exhaust passages, exhaust-ports that communicate with the latter as the valve reciprocates, two small passages conducting live steam to ends of steam-chest, and supplemental exhaust-ports 10, which extend from the spaces formed alternately at ends of valve-chamber to the main exhaust-passages, as shown and described.

3. The valve and steam-chest having a flat base provided with central and end ports and a curved exhaust-passage 9, formed as a 75 groove or depression in said base, and the piston and cylinder having a flat top provided with the steam-passages 5, 5^a, 9^a, and 8, 8^a, a portion of the latter being formed as grooves extended in the flat top, the said passages being arranged to coincide and communicate with those of the steam-chest base, substantially as shown and described.

4. The combination, with the steam-chest having a cylindrical chamber, of a cylindrical 85 valve, and a lateral guide fixed on the steam-chest the same working in a guide-cavity in the valve to prevent rotation, substantially as shown and described.

JAMES SEBBORN ATKINSON.
